UNITED STATES PATENT OFFICE

WILLARD JORDAN SLAGLE, OF CAMBRIDGE, MASSACHUSETTS, ASSIGNOR TO DEWEY AND ALMY CHEMICAL COMPANY, OF CAMBRIDGE, MASSACHUSETTS, A CORPORATION OF MASSACHUSETTS

RUG UNDERLAY

No Drawing.

Application filed October 10, 1930. Serial No. 487,922.

This invention relates to anti-slipping underlays for floor coverings, such as rugs and the like, and it consists of sheet material, such as paper, and the like, preferably creped and rubberized on both sides whereby it is adapted as an underlay for, and in combination with, a floor covering to prevent relative sliding motion between said floor covering and a floor, all as more fully hereinafter described and claimed.

Floor coverings, such as rugs for example, are, unless permanently positioned on a floor, notoriously slippery under foot. The tendency of rugs and other floor coverings to slide on a floor under the impulse of the user's foot, and particularly when the floor is highly finished or polished as to surface, is due to the very low coefficient of friction of the contacting surfaces.

I am aware that various underlays for floor coverings have been proposed heretofore, all designed to increase stability of the floor covering on the floor under impact; but so far as I know, all these suggested expedients involved either an underlay of textile material which disadvantageously increased the thickness of the floor covering and were cumbersome as well as expensive, or consisted in the application to the under-surface of the floor covering of a friction-increasing adhesive material which disadvantageously affected cleaning and frequently resulted in permanent damage to the floor covering itself.

It is an object of the present invention to provide an underlay for floor coverings which, while effective to prevent slipping, will not be cumbersome or expensive and which will not detrimentally affect either the floor covering or the floor.

In the preferred embodiment of this invention, I surface both sides of a sheet of kraft paper, preferably creped to 33% stretch and of about 60 pounds to the ream, with a thin adherent coating of a vulcanized rubber compound which is not so thick as to interfere with the creping qualities of the paper, and is adapted to afford frictional resistance to motion between the paper and

the floor and between the floor covering and the paper.

While smooth rubberized paper will function satisfactorily when clean, i. e. relatively free of dust, and with floor covering having a relatively smooth under-surface, in general and particularly for rugs having relatively rough under-surface I prefer a rubberized crepe paper. The crepe paper underlay of this invention is not disadvantageously affected by dust as is a smooth underlay. It is thought that the dust, which in the case of the smooth underlay tends to lower the frictional resistance to motion, becomes segregated in the creases of the crepe paper out of contact with the floor or floor covering. Furthermore, the creping results in a normally small contact area, between the underlay and the floor, which permits the floor covering and underlay to be readily moved about on the floor when desired. But, under the weight of the foot, the creping is deformed with a consequent great local increase in effective contact area, which is of advantage.

An underlay according to this invention may be made in any of the several ways well known in the art; but I prefer to spray ordinary 60 pound crepe kraft paper, or its equivalent, with an aqueous dispersion of rubber and suitable vulcanizing, accelerating, and anti-oxidation agents. In order to obtain and maintain a high coefficient of friction at the rubber surface the rubber compound should be of the "pure gum type", i. e. lightly vulcanized rubber substantially free from loading fillers. Furthermore, the compound should be non-blooming and protected from oxidation by means of any of the well-known antioxidants. A wide choice of coloring agents, accelerators, and rubber drugs generally is available; and those skilled in the art will have no difficulty in choosing a compound suitable for the purpose of this invention providing only that they avoid "blooming", i. e. migration of sulfur to the surface, which greatly reduces the coefficient of friction. Antioxidants are indicated in the interest of long-service life but are 100

not otherwise requisite to the function of the rubber surfacing.

I usually prepare the material of this invention in long rolls from which suitably sized pieces may be cut to fit small rugs or several lengths may be assembled with or without effecting a cementitious bond as the user may desire. In general, I find it satisfactory to lay down parallel strips of the proper length without attempting any marginal bonding as the frictional resistance to motion is such that the relative position of the several strips of a large underlay and the superimposed rug is maintained.

15 By the term "rubber" I mean any elastic compound having the desired characteristics of flexibility and high coefficient of friction without adhesive affinity for other solids.

I claim:

20 1. An underlay for floor coverings comprising a sheet of creped paper presenting on both faces thereof a surface having a high coefficient of friction but no adhesiveness.

25 2. An underlay for floor coverings comprising a sheet of creped paper having both faces surfaced with a thin coating of vulcanized rubber.

3. An underlay for floor coverings comprising a creped material, at least one face thereof being provided with a rubber friction surface.

35 4. An underlay for floor coverings comprising a creped material, at least one face thereof being provided with a surface of vulcanized rubber.

5. An underlay for floor coverings comprising a creped material, its opposite faces being provided with rubber friction sur-

40 faces.

6. An underlay for floor coverings comprising a creped material, having applied thereto a film of vulcanized rubber, said film being of a thickness not to interfere

45 with the creping of the material.

7. An underlay for floor coverings comprising a sheet of creped paper having both faces surfaced with a thin coating of vulcanized rubber.

50 8. An underlay for floor coverings comprising a sheet of creped paper, having applied thereto on opposite faces a film of vulcanized rubber, said film being so thin as not to interfere with the creping.

55 Signed by me at Cambridge, Massachusetts this 3rd day of October 1930.

WILLARD J. SLAGLE.
